Primary Examiner — Katherine A Holbrow(74) *Attorney, Agent, or Firm* — Build IP, LLC; Robert V. Donahoe(57) **CLAIM**

The ornamental design for a game board with playing surface, as shown and described.

DESCRIPTION

The FIGURE is a top view of a game board with playing surface showing the new design.

The outermost broken line perimeter shows the game board, and forms no part of the claimed design.

All other broken lines show portions of the playing surface and form no part of the claimed design.

1 Claim, 1 Drawing Sheet(56)
